UNITED STATES PATENT OFFICE.

ALLIE S. FREED, OF NEW YORK, N. Y.

DESIGN FOR A COMBINED MOTOR-VEHICLE BODY AND HOOD.

Application filed June 13, 1927. Serial No. 22,417. Term of patent 14 years.

To all whom it may concern:

Be it known that I, ALLIE S. FREED, a citizen of the United States, residing at New York, in the county of New York and State of New York, have invented a new, original, and ornamental Design for a Combined Motor-Vehicle Body and Hood, of which the following is a specification, reference being had to the accompanying drawing, forming part thereof.

In the drawing—

Figure 1 is a side elevation of a combined motor vehicle body and hood, showing my new design;

Figure 2 is a rear elevation thereof; and Figure 3 is a front elevation thereof.

I claim:

The ornamental design for a combined motor vehicle body and hood, as shown.

ALLIE S. FREED.
